UNITED STATES PATENT OFFICE.

HARRY WILLSHAW, OF BUFFALO, NEW YORK, ASSIGNOR TO DUNLOP TIRE AND RUBBER CORPORATION OF AMERICA, OF BUFFALO, NEW YORK, A CORPORATION OF NEW YORK.

DESIGN FOR A TIRE TREAD.

Application filed April 1, 1924. Serial No. 9,127. Term of patent 14 years.

To all whom it may concern:

Be it known that I, HARRY WILLSHAW, a subject of the King of Great Britain, and a resident of Buffalo, county of Erie, and State of New York, have invented a new, original, and ornamental Design for Tire Treads, of which the following is a specification, reference being had to the accompanying drawing, forming a part thereof.

Fig. 1 is a sectional perspective view; and Fig. 2 is a sectional plan view of a tire showing my new design.

I claim:—

The ornamental design for a tire tread as shown.

In witness whereof, I have hereunto signed my name.

HARRY WILLSHAW.
